US0D1042200S

(12) **United States Design Patent** (10) Patent No.: **US D1,042,200 S**
(45) Date of Patent: ** Sep. 17, 2024

(54) **WATCH**

(71) Applicant: **Anhui Huami Health Technology Co., Ltd.**, Anhui FTZ (CN)

(72) Inventors: **Wenjian Xu**, Hefei (CN); **Wei Zheng**, Hefei (CN); **Zhijun Liao**, Hefei (CN)

(73) Assignee: **Anhui Huami Health Technology Co., Ltd.**, Anhui FTZ (CN)

(**) Term: **15 Years**

(21) Appl. No.: **35/517,272**

(22) Filed: **May 24, 2022**

(80) **Hague Agreement Data**

Int. Filing Date: **May 24, 2022**

Int. Reg. No.: **DM/221603**

Int. Reg. Date: **May 24, 2022**

Int. Reg. Pub. Date: **May 26, 2023**

(51) **LOC (14) Cl.** **10-07**

(52) **U.S. Cl.**

USPC **D10/128**; D10/32; D14/344

(58) **Field of Classification Search**

USPC D10/30-39, 128, 132; D14/344; D11/3
CPC G04G 9/00; G04G 17/00; G04G 17/08;
